(57) **CLAIM**

The ornamental design for a portable tray, as shown and described.

DESCRIPTION

FIG. 1 is a top perspective view of a first embodiment of the portable tray;

FIG. 2 is a bottom perspective view of the portable tray;

FIG. 3 is a right side elevation view of the portable tray;

FIG. 4 is a left side elevation view of the portable tray;

FIG. 5 is a front elevation view of the portable tray;

FIG. 6 is a rear elevation view of the portable tray;

FIG. 7 is a top plan view of the portable tray;

FIG. 8 is a bottom plan view of the portable tray;

FIG. 9 is a top perspective view of a second embodiment of the portable tray;

FIG. 10 is a bottom perspective view of the portable tray of FIG. 9;

FIG. 11 is a right side elevation view of the portable tray of FIG. 9;

FIG. 12 is a left side elevation view of the portable tray of FIG. 9;

FIG. 13 is a front elevation view of the portable tray of FIG. 9;

FIG. 14 is a rear elevation view of the portable tray of FIG. 9;

FIG. 15 is a top plan view of the portable tray of FIG. 9; and, FIG. 16 is a bottom plan view of the portable tray of FIG. 9.

The broken lines in the drawings depict portions of the portable tray which form no part of the claimed design.

1 Claim, 12 Drawing Sheets
